UNITED STATES PATENT OFFICE.

CARL RICHTER, OF CHICAGO, ILLINOIS.

DESIGN FOR A BOTTLE.

SPECIFICATION forming part of Design No. 21,495, dated April 19, 1892.

Application filed May 2, 1891. Serial No. 391,416. Term of patent 7 years.

To all whom it may concern:

Be it known that I, CARL RICHTER, a citizen of the United States, residing at Chicago, in the county of Cook and State of Illinois, have 5 invented and produced a new and original Design for Beer-Bottles, of which the following is a specification.

This design has for its object to provide a novel and ornamental beer-bottle which presents to the eye a distinguishing and characteristic appearance.

The leading feature of the design resides in a cylindro-conoidal beer-bottle having a flat-faced circular projection located a little above 15 the point where the lower cylindrical portion of the bottle passes into the conoidal or tapered upper portion and connected with the bottle by crescent-shaped side portions, the upper and lower peripheral points of the flat-faced circular projection being substantially 20 in the plane of the exterior surface of the bottle.

The design is illustrated by the accompanying drawing, in which the figure is an elevation of a beer-bottle embodying my design.

In the drawing, the numeral 1 indicates the lower portion of the beer-bottle, which is cy-

lindrical in form or contour and passes into a conoidal or tapered portion 2, comprising about one-half the length of the bottle. A 30 little above the point where the cylindrical portion passes into the conoidal or tapered portion is located the flat-faced circular projection 3, the upper and lower peripheral portions 4 of which are arranged in or nearly in 35 the plane of the surface of the bottle. The circular projection is connected with the bottle by crescent-shaped portions, as at 6. A bead 7 in low relief surrounds the flat-faced circular projection. 40

The design provides a beer-bottle which presents to the eye an ornamental, distinguishing, and characteristic appearance.

What I claim is—

The design for a beer-bottle, herein shown 45 and described.

In testimony whereof I have hereunto set my hand and affixed my seal in presence of two subscribing witnesses.

CARL RICHTER. [L. S.]
